US00D933192S

(12) **United States Design Patent** (10) **Patent No.:** **US D933,192 S**
(45) **Date of Patent:** **** Oct. 12, 2021**

(54) **SUCTION HOOD**

(71) Applicant: **ATLAS COPCO AIRPOWER,
NAAMLOZE VENNOOTSCHAP,
Wilrijk (BE)**

(72) Inventors: **Prashant K. Rajput**, Maharashtra (IN);
Vishal Krishnarao Patil, Maharashtra (IN);
Vijay Sohanlal Sharma, Maharashtra (IN); **Srinivasan Arjune**, Tamil Nadu (IN)

(73) Assignee: **ATLAS COPCO AIRPOWER,
NAAMLOZE VENNOOTSCHAP,
Wilrijk (BE)**

(**) Term: **15 Years**

(21) Appl. No.: **29/731,409**

(22) Filed: **Apr. 15, 2020**

(30) **Foreign Application Priority Data**

Mar. 16, 2020 (EM) 007756754-0002

(51) **LOC (13) Cl.** **23-04**

(57) **CLAIM**

The ornamental design for a suction hood, as shown and described.

DESCRIPTION

FIG. 1 is a perspective view of the suction hood.

FIG. 2 is a top view thereof.

FIG. 3 is a bottom view thereof.

FIG. 4 is a right side view thereof.

FIG. 5 is a back view thereof.

FIG. 6 is a left side view thereof; and,

FIG. 7 is a front view thereof.

The broken lines in the figures illustrate portions of the article which form no part of the claimed design.

1 Claim, 7 Drawing Sheets
